[57] CLAIM

The ornamental design for a universal bearing bracket, as
shown and described.

DESCRIPTION

FIG. 1 is a front, end perspective view of a universal bearing bracket;

FIG. 2 is a rear perspective view thereof; and,

FIG. 3 is an end view thereof with the opposite end view
being unornamented.

The broken line showing of partial structure is for illustrative
purposes only and forms no part of the claimed design.
